SAFETY MEANS FOR HAND BAGS OR THE LIKE

Filed Jan. 24, 1924

Inventor,
John P. Williams,
By *John Fred Little*
Attorney.

UNITED STATES PATENT OFFICE.

JOHN P. WILLIAMS, OF NEW YORK, N. Y., ASSIGNOR TO DUPLEX ELECTRIC COMPANY, OF NEW YORK, N. Y., A CORPORATION OF DELAWARE.

SAFETY MEANS FOR HAND BAGS OR THE LIKE.

Application filed January 24, 1924. Serial No. 688,258.

This invention relates to safety means for hand bags or the like, and it has particular relation to an improved means for protecting hand bags, or similar receptacles for containing and carrying valuables, against loss by inadvertence or by an attempted attack to grasp the bag or receptacle from the hand of the user or to remove such bags or receptacles from the person of the user.

To these ends my invention comprises safety means whereby the hand bag or receptacle, when in use and carried in the hand or on the person, will be directly anchored or attached and secured in connection to the arm of the user.

In the drawings—

Figure 1 is a perspective view of a hand bag having one form of safety means as comprised in my invention.

Fig. 2 is an edge view of the construction shown in Fig. 1, and illustrating the control of the opening of the bag by the safety means, the open position being shown in dotted lines.

Fig. 3 is a perspective view of another form of the safety means, as adapted for and carried by heavy bags.

Corresponding parts in all the figures are denoted by the same reference characters.

Referring to the drawings, 14 designates a bag or receptacle for carrying valuables, which may be of any usual or adapted construction and of any type in common vogue or use, such as a lady's hand bag or purse, heavy messenger's bag, brief-case, travelling bag, or the like.

15 designates a bracelet member, as comprised in my improved safety means, which constitutes the anchoring or attaching device which is secured in connection with the wrist or arm of the user. This bracelet member may be of any usual or adapted construction, such as a ring-bracelet surrounding and worn upon the forearm, as shown in Fig. 1, or a wristlet consisting of a band of leather or pliable material strapped or otherwise secured around the arm of the user, as indicated in Fig. 3.

A flexible connecting member, 16, extends between the bracelet member 15 and the bag or receptacle 14, and is of desired longitudinal extent, according to the circumstances and conditions of use, and of any suitable or adapted construction. I have herein

shown the connecting member as consisting of a chain, either in a single length (as in Fig. 3), or a split length (as in Fig. 1) affording two terminal ends, as at 17—17, for connection to the bag 14.

Connection means, indicated at 18 are provided between one terminal end of the connecting member 16 and the bracelet member 15, and such means may be of any suitable or adapted construction for fastening the connecting member 16 either detachably or permanently to the bracelet member. I have shown such connection means 18, in Fig. 1, as consisting of a snap-hook carried at the end of the flexible connecting member and detachably engaging an eye or ring, 19, fixed to the bracelet member, while in Fig. 3 such connection means is shown as a ring, 20, carried at the end of the flexible connecting member and detachably engaging a snap-hook 18 carried upon one of the securing straps of the wristlet bracelet member 15. It will be understood that the connection of the flexible member 16 with the bracelet member 15 may be at any suitable or adapted part of the latter.

Connection means, indicated at 21, are also provided between the other terminal end of the flexible connecting member 16 and the bag or receptacle 14, and such means may likewise be of any suitable or adapted construction for fastening the connecting member 16 either detachably or permanently to any part of the bag 14. I have herein shown such connection means 21 as consisting of a snap-hook carried at the end of the flexible connecting member and detachably engaging an eye or ring, 22, carried by the bag or receptacle 14.

In the type of construction illustrated in Fig. 1, with a split length of the connecting member 16, the respective terminal split lengths of such member have their connection 21 at opposite sides of the opening or mouth of the bag 14, so that the connecting member operates to retain the opening of the bag closed. Thus, should the bag be dropped from the hand, the gravity weight of the bag operating in conjunction with such opposite mouth connections of the flexible suspending member 16 will retain the bag closed against accidental opening.

A slide-ring, 23, may be mounted upon the split portion of the connecting member 16 to

tighten the same in operative action just above described or to control the spread of the split portion as desired, and in association with the connection means 18 and 21 at 5 the respective terminal ends of the connecting member 16, any suitable pad-lock or other supplementary safety securing devices, as indicated at 24, Fig. 3, may be employed to enhance the safety and security of the 10 connection.

It will be understood that the bag or receptacle 14 may be provided with the usual handle, 25, for carriage in the hand in the usual or normal manner independent of the 15 safety means as comprised in my invention.

The operation and advantages of my invention will be readily understood. In practice, the bracelet member 15 is mounted and retained upon the arm or wrist and the flexible 20 connecting member 16 extends as a free length between the bracelet and the bag or receptacle and in secure connection with both the bag and bracelet, leaving the bag free to be carried in the hand in the usual manner. The operative conditions thus preclude the inadvertent laying down of the bag and leaving the same unprotected, as it is in attached connection to the person of the wearer; or the accidental dropping of the 25 bag, as it will be retained suspended and in connection with the person of the wearer by the safety means, in the event that the hand-hold upon the bag is released; or should an attempt be made to grasp the bag 30 and tear it from the hand, the safety means is operative to not only securely retain the bag in its attached connection with the person of the user but also to signal the attack by the pull upon the arm.

In conditions of use with large bags and a 40 strong wristlet member 15 and heavy connecting member 16, such as bags carried by bank messengers or others for the transportation of securities or currency, my invention affords a safe and effective means to prevent or retard successful burglarous attack, and in the case of ladies' hand-bags the improved safety means can be made an 45

attractive adjunct to the usual bag by construction in the type of the jeweller's art. 50

Under some conditions of use, where the protected bag or receptacle is carried in the pocket or within the clothing of the user, the flexible connecting member 16 may be worn to extend from the arm or bracelet 55 member 15 up within and through the sleeve of the clothing to the bag or receptacle, thus concealing the safety means and protected status.

I do not desire to be understood as limiting myself to the detail features of construction and arrangement as herein shown and described, as it is manifest that variations and modifications therein may be resorted to, in the adaptation of my invention to varying conditions of use, without departing from the spirit and scope of the invention and improvements. I therefore reserve the right to all such variations and modifications as properly fall within the scope of my invention and the terms of the following claim. 70

Having thus described my invention, I claim and desire to secure by Letters Patent:

A safety means of a class described, comprising a securing member for attachment to the person of the user, a flexible connecting member extending longitudinally from said securing member and having plural lengths, connection means between the initial end of said connecting member and said securing member, detachable connection means respectively carried at the terminal ends of the plural lengths of said connecting member for detachable attachment to opposite sides of the spread or hinge mouth opening of a hand bag or receptacle, and means for bringing together the plural lengths of said connecting member, whereby the connecting member will be operative in attachment to lock the mouth of the bag or receptacle against opening accidentally or under gravity action. 75 80 85 90 95

In testimony whereof I have signed the foregoing specification.

JOHN P. WILLIAMS.
